UNITED STATES PATENT OFFICE

159,095

BALL POINT PEN

William Peterson and Joseph A. Barnett, Chicago,
Ill., assignors to A. B. A. Corporation, Chicago,
Ill., a corporation of Illinois

Application April 7, 1949, Serial No. 1,852

Term of patent 14 years

(Cl. D74—17)

To all whom it may concern:

Be it known that we, Joseph A. Barnett, a citizen of the United States, residing at Chicago, in the county of Cook and State of Illinois, and William Peterson, a citizen of the United States, residing at Chicago, in the county of Cook and State of Illinois, have invented a new, original, and ornamental Design for Ball Point Pens, of which the following is a specification, reference being had to the accompanying drawings, forming a part thereof.

In the drawings:

Fig. 1 is a side elevation of a ball point pen embodying our new design;

Fig. 2 is a side elevation, the cap being removed;

Fig. 3 is a perspective view of the cap removed from the body of the pen.

Fig. 4 is a side elevation of the pen with the cap telescoped with the closed end of the body of the pen.

We claim:

The ornamental design for a ball point pen, substantially as shown.

WILLIAM PETERSON.
JOSEPH A. BARNETT.
